UNITED STATES PATENT OFFICE.

CHARLES A. LOWE, OF GREEN RIVER, ILLINOIS.

DESIGN FOR A HAY-RACK CLEAT.

52,664.

Specification for Design.

Patented Nov. 12, 1918.

Application filed June 26, 1916. Serial No. 106,077. Term of patent 3½ years.

To all whom it may concern:

Be it known that I, CHARLES A. LOWE, a citizen of the United States, residing at Green River, in the county of Henry and State of Illinois, have invented a new, original and ornamental Design for a Hay-Rack Cleat, of which the following is a specification, reference being had to the accompanying drawing, forming a part thereof.

The figure is a perspective view of a cleat showing my new design.

I claim:—

The ornamental design for a hay rack cleat as shown.

CHAS. A. LOWE.
